FINGER RING

Abraham G. Sager, 910 W. Jackson Blvd.,
Chicago, Ill. 60607

Filed May 18, 1966, Ser. No. 2,374

Term of patent 14 years

(Cl. D45—10)

Fig. 1.

Fig. 4.

Fig. 2.

Fig. 3.

FIG. 1 is a front perspective view of a finger ring showing my new design;

FIG. 2 is a top plan view thereof;

FIG. 3 is a side elevational view thereof, and

FIG. 4 is an enlarged fragmentary sectional view taken on line 4—4 of FIG. 1 in the direction indicated by the arrows.

I claim:

The ornamental design for a finger ring, as shown.
